U S P A T E N T O F F I C E.

JAMES BAILLIE HAMILTON, OF HAMMERSMITH, COUNTY OF MIDDLESEX,
ENGLAND.

REED-ORGAN.

SPECIFICATION forming part of Letters Patent No. 293,454, dated February 12, 1884.

Application filed October 2, 1883. (No model.) Patented in England September 7, 1883, No. 4,312.

To all whom it may concern:
Be it known that I, JAMES BAILLIE HAMILTON, gentleman, a subject of the Queen of Great Britain, and residing at Studland Street, 5 Hammersmith, county of Middlesex, England, have invented certain Improvements in Reed-Organs or like Musical Instruments, (for which I have obtained a patent in Great Britain, No. 4,312, dated September 7, 1883,) of which the 10 following is a specification.

In cases where the pallet or valve precedes the reed, as is usual in pipe-organs, it is desirable to bring the reeds as close as possible to the pallets, so as to make the intervening space 15 as small as possible, as the said space, if excessive, interferes with the prompt speech of the notes. This part of my invention has for its object to effect this desired close proximity of the reeds and pallets without, on the one 20 hand, keeping the bars of the sound-board too deep for the proper speech, or, on the other hand, too shallow for the requisite strength and stiffness, seeing that the pallets depend for their efficiency upon the perfect straightness and rigidity of the bars.

I will describe my invention with reference to the accompanying drawings, wherein Figure 1 is a transverse section, Fig. 2 a longitudinal section, and Fig. 3 a plan, of so much 30 of an instrument as is necessary to illustrate my invention.

According to my said invention I make a fixture of the superstructure, thus enabling the bars *a* of the sound-board *A* to be shallow 35 and yet rigid, and allowing also the reeds *b* to be situated as close as is desired to the pallets *c* and to each other; and I moreover provide a more convenient and perfect mode of access to the reeds, for tuning or other purposes. I 40 effect this by means of a plug of wood or breech-piece, *D*, which contains all the reeds common to the pallet which it overlies, there being such a plug or breech-piece for each such set of reeds controlled by one pallet. The reeds 45 are supported or held on the sides of the plugs or breech-pieces toward the pallets, and a hole, *d*, passes through the plug or breech-piece *D*, above each reed, allowing it to communicate with its corresponding orifice *e* above, which 50 is controlled by a slide, *f*, of the ordinary kind.

Each breech-piece or plug *D* passes between the bars *a* of the sound-board, the said plugs being provided with projecting pieces *d'* at each end, which hold the said breech-pieces or plugs against the table *g*, which covers the bars 55 *a* of the sound-board, and also keep the reeds from actual contact with the pallets. The said projections on the plugs or breech-pieces also close air-tight at back and front the entrances between the bars of the sound-board. In order to properly develop the tone after the current of air has passed through the reed, plug, and slide-hole, I fix over the upper board, beneath which the slides work, a board, *H*, (which I term the "cavity-board" or "honey-comb," 60 from its appearance,) having therein holes or spaces *h*, corresponding to the reeds, and of the diameter or width admissible by the scale of the instrument. In order to widen out this scale without increasing the length of the instrument, I provide a row of holes or spaces, *h'*, at each side of the series of first-named holes or spaces, the former opening into the latter by passages *h''* at alternate sides. Thus the side holes, *h'*, can be double the diameter 70 75 or capacity of the central holes or spaces, *h*. I call the larger holes, *h'*, "mouths," and the smaller ones, *h*, "nostrils." By inserting plugs or vent-pegs *i* into the nostrils *h*, I am able to regulate the sides of the passages *h'*, which 80 communicate with the mouths *h'*, either by raising or lowering the plugs, or by turning them. The plugs may also be hollow and prolonged into a tube, as shown, its length and closure greatly affecting the tone. The mouths 85 may be treated in the same way; but I prefer, as a rule, to allow the cavity-board to diminish in depth from bass to treble in such a way that by merely boring holes I secure the depth of mouths and nostrils required. The said 90 mouths may be further shaded or shielded by any device commonly in use for such a purpose.

As regards the artificial excitation of any note that may be naturally slow of speech, I 95 take advantage of the proximity of the pallet to the reed and place upon the pallet a light spring, *h*, as shown in Fig. 2, which spring, when the pallet is closed, slightly forces the reed into its own orifice. When the pallet is 100

depressed, the release of the pressure effects a recoil upon the reed-tongue, which precipitates the act of vibration. This spring h preferably acts upon the ligature l or cross-bar 5 of my compound reeds, as described in the specification of my prior patent; and in order to prevent its catching the reeds as they are withdrawn, it is curved into a "hump" and its free end is buried in a cavity bored out of 10 the substance of the pallet. The said spring is preferably flat, and covered with leather or other soft substance at h^2 , so as to prevent it jarring on the return of the pallet.

There may be placed over a whole stop or 15 series of notes, to assist in developing the tone, a further inclosure, M , as shown in Fig. 1, in the form of a tube running the length of the instrument and common to every note in the stop, the orifices of which open into it. The 20 said tube will be more expanded toward the treble, so that the treble-notes have the advantage of the wide open mouth, while the bass have the benefit of the tube, which becomes longer as the notes deepen.

25 The invention may be used in combination with ordinary single reeds, or with my own patent double-treble or compound reeds.

I am aware that musical instruments have heretofore been provided with removable 30 reeds, and therefore do not claim this, broadly.

I claim as my invention—

1. The combination of the sound-board of a reed-instrument and a series of pallets with a corresponding series of removable plugs or breech-pieces, each carrying two or more reeds common to one pallet and adapted to recesses in the sound-board, substantially as set forth. 35

2. The combination of the sound-board of a reed-instrument, having a series of spaced bars, a , with reeds and pallets near together, 40 and with a superstructure rigidly secured to the sound-board through said bars, substantially as described.

3. The combination of the sound-board, 45 reeds, and pallets of a musical instrument, with a cavity-board having a communicating nostril, h , and mouth h^2 for each reed, substantially as specified.

4. The combination of the reeds of a musical instrument with pallets carrying exciting-springs h , adapted to come into contact 50 with the reeds, substantially as set forth.

In testimony whereof I have signed my name to this specification in the presence of two subscribing witnesses.

JAMES BAILLIE HAMILTON.
